UNITED STATES PATENT OFFICE.

MICHAEL HENRY REAP, OF SCRANTON, PENNSYLVANIA.

REGULATOR FOR SEPARATORS.

1,217,826.

Specification of Letters Patent. Patented Feb. 27, 1917.

Application filed February 24, 1915. Serial No. 10,261.

To all whom it may concern:

Be it known that I, MICHAEL HENRY REAP, a citizen of the United States, residing at Scranton, in the county of Lackawanna and State of Pennsylvania, have invented certain new and useful Improvements in Regulators for Separators, of which the following is a specification, reference being had therein to the accompanying drawings.

10 This invention comprises an automatic regulator for so called jigs, separators, or other apparatus for the segregation of materials into various grades. It is especially adapted for use where the separation is effected through, and based upon variations in the specific gravities of the materials used.

Separators of this type generally consist of a feed and bed or screen for the materials to be segregated: outlets for the heavier and lighter portions respectively: a liquid tank under the bed or screen: and means for forcing the liquid up through the materials on the screen. The heavier portions remain thereon and are drawn off through a port or valve; the lighter portions ascend and pass over a gate; while the finer particles pass through the mesh of the screen.

For perfect working of the apparatus, it is desirable that a certain approximately fixed proportion of the heavier materials remain on the bed or screen at all times, the amount varying according to the quality, quantity, and various characteristics of the material being used. As this amount is being constantly augmented, considerable difficulty has been experienced in withdrawing portions of the heavier materials to the exclusion of the lighter grade above, and at the same time maintaining the line of demarcation between these two grades at an approximately fixed level.

Electrical apparatus to energize a clutch and connect the heavy material valve with the drive shaft after the material has reached a certain level, has been provided. This is complicated, expensive, and owing to the excessive moisture and dust, frequently ineffective. Devices wherein a valve is connected with a counterweight, and released after the weight of the heavier material has overcome the counterweight, are uncertain, as frequently the bed becomes covered with bolts, nails, spikes, and portions of machinery which are generally

much heavier than the heaviest of the materials to be separated.

A practical device which will eliminate these difficulties and produce the desired results, should be simple, automatic, and so constructed that any variation in the height of the heavier materials on the bed will be immediately and positively communicated to the outlet members, and the primary object of the present invention is the production of such a device. Other objects and advantages will in part be obvious, and in part be made clear in the description which follows.

In the accompanying drawings there is illustrated a practical embodiment of the invention, the following views being shown:

Figure 1, is a side elevation, partly in section, showing an application of a form of the device;

Fig. 2, is a plan view of the same;

Fig. 3, is a sectional view showing outlets in detail;

Fig. 4, is a side elevation, partly in section, showing a modification;

Fig. 5, is a plan view of the same;

Fig. 6, is a side elevation, partly in section, of another embodiment of the invention; and

Fig. 7, is a plan view of the same.

Referring specifically to the drawings, the numeral 1, designates generally a so called jig, or separator of well known construction. It consists essentially of a tank 2, a plunger 3 for forcing liquid up through a bed or screen 4, upon which are fed materials to be separated, through any suitable feed, 5.

The heavier portions of the material remain on the screen, and the lighter pass over a gate 6 into a trough or conveyer 7. For carrying off the heavier portions there is provided a valve 8 carrying a ratchet member 9. Engaging with the ratchet is a pawl 10 carried by a rock arm 11, which is driven by an arm 12 generally connected eccentrically with the drive shaft of the plunger. Actuation of the rock arm back and forth rotates the valve, and carries the heavier materials from the edge of the screen and deposits them in a trough or the like 13. This is all well known construction, and no claim is made thereto.

My invention comprises means for posi-

tively transmitting to the outlet opening and closing means or instrumentality, any variation in the height of the line of demarcation between the heavy and lighter materials, and will now be described.

In Figs. 1 and 2, a preferred embodiment for use on the particular form of separator illustrated therein, is shown. It comprises a float member having a body portion 14 sufficiently heavy to overcome the lighter materials, and normally rest upon the surface of the heavier portions. It is preferably provided with a guide rod 15 adapted to extend through a perforation in the bed 15 or screen, and be disposed on the body portion of the float, preferably at the bottom thereof. The construction, buoyancy and adjustments of the float are so designed, that, while the bottom rests upon the surface 20 of the heavier materials, the top will extend up through the lighter portions and clear of the liquid level line. For the purpose of preventing materials from lodging on the float, it is provided, at its upper portion, 25 with sloping sides.

This float member or weighted float member, as it may be called, is suitably connected, as by rods 16 provided with connecting members 17 and adjusting means 18, to an 30 arm or lever 19 mounted, preferably adjustably, on a shaft 20. Shaft 20 is carried by bearings 21 here shown mounted on the sides of the separator.

Upon the shaft 20 there is secured, 35 through an adjusting means 22, a second arm 24. This arm is provided with an extended portion 25, so arranged that the end of the arm will be in approximate alinement with the pawl for actuating the discharge 40 valve 8 previously described. Intermediate the ends a counter weight 26 is arranged so as to be movable longitudinally thereon.

The pawl 10 is connected with the end of the extended portion 25 of the arm 24 as by 45 pivotal connections 27, rods 28, and adjusting means 29, and will, through the oscillations of the rock arm 11 actuate the valve 8 to carry off the heavier portions of the material when in the position shown in Fig. 1.

50 It will be apparent that when the heavy materials have reached a pre-determined height, raising of the float will be communicated through the connections just described positively and directly to the pawl to actuate 55 the discharge valve, and the adjustments permit a certain necessary amount of lost motion, or jumping of the float due to the pulsations of the water without effecting actuation of the valve. These adjustments 60 likewise permit a very accurate determination of the height of the heavier materials on the screen.

For regulation of separators wherein there is provided a form of waste valve differing 65 in construction from that just described, or

wherein the heavier materials are permitted to pass under a gate, the embodiments illustrated in Figs. 4, 5, 6, and 7 may be desirable. It will be understood however, that with slight modification, these forms may be 70 combined as occasion may require.

Referring to Figs. 4, and 5, a float, or weighted float member 30, is, as before, adapted to rest normally on the surface of the heavier materials. It is pivotally connected, as by connection member 31, to an arm 32 extending from and secured to a shaft 33. This shaft is mounted suitably, as in journals 34, conveniently placed, and here shown secured to the sides of the separator. 80

Upon the shaft 33 there are also provided two arms 35, and there may also be secured an extension arm 36 for the reception of a counterweight 37 adjustably mounted.

Pivoted to the arms 35, as by 85 connection members 38, are rods 39, which are at their opposite ends secured, preferably pivotally, to a gate 40. The connection members are arranged so as to permit their longitudinal adjustment on the arms 35, and 90 also to effect an adjustment of the rods 39 vertically therein. The gate 40 is arranged to slide in guideways 41 secured to the sides of the separator, and is provided with a lip or extension 42 hingedly secured thereto. 95 Both are adapted to normally rest in proximity to the permanent gate of the separator.

The float 30, arms 32 and 36, and counterweight 37 may be dispensed with in this construction, and floats 43, pivotally, and preferably adjustably secured to extended portions 44 of the arms 34, substituted, according to the construction of the separator, and the conditions under which it is to be operated. 105 This construction is shown in dotted lines, in Fig. 5.

It will be apparent that raising of the float or floats in this embodiment will be communicated, through the arms and shaft 110 to the gate, positively, and in the same direction as the float, the adjustments permitting a high degree of accuracy in fixing the level of the heavier materials under all working conditions.

115 In Figs. 6, and 7, floats 45 are suitably attached, as by pivotal members 46, to the ends of lever arms 47, which are in turn mounted, preferably adjustably, and intermediate their ends, on a supporting member 120 or shaft 48. Similarly, a supporting member or shaft 49 carries mounted at suitable points intermediate their ends to secure proper leverage, arms 50. The supporting members or shafts are in turn mounted in 125 bearings 51 conveniently placed, and here shown attached to the separator.

Lever arms 47 and 50 are connected, as by slotted link connections 52, the opposite ends of arms 50 being in turn connected as by 130

links 53 pivotally mounted therein, to a gate 54. This gate is adapted to slide vertically in guideways 55 here shown mounted on opposite sides of the separator, and is, as before, provided with a lip or extension 56 hingedly connected thereto. Both gate portions are arranged to normally rest in proximity to the main gate 6.

Provision is made to permit a normal amount of rise or jump of the floats due to the pulsations of the liquid without effecting an actuation of the outlet for the materials. A simple means for doing this is shown in Fig. 6, wherein an elongated slot 57 is provided in a portion of the members 46 through which the floats are attached to the lever arms 47.

By providing a lost motion connection between the float and the outlet opening and closing means, the float is permitted a limited amount of movement in each direction, due to the pulsations of the liquid, without communicating this movement to the outlet opening and closing means. As the heavier materials increase or diminish, this movement becomes more restricted until finally the float and connecting instrumentality act as an integral or unitary structure, directly and positively upon the port opening and closing means. The pulsations of the liquid at this stage of the movement, cause a vibratory or jarring motion which forces the gates through the coarser particles of material much more efficiently than would be possible if a steady and direct pressure were applied.

In Figs. 4, 5, 6, and 7, there is shown a form of outlet valve wherein provision is made for continuous rotation, this being a well known construction, a drive member 58 through the medium of a reducing gear 59 being used.

The operation of the form shown in Figs. 6, and 7, is apparent, as raising of the floats is communicated positively, and in the same direction, through the lever arms and links, to the gate 54, to raise the same, and lowering of the floats lowers the gate.

The terms "directly" and "positively" as used to describe the manner in which movement of the weighted or float member is communicated to the outlets, should be distinguished from electrical means for energizing a clutch, to connect the drive gear with the valve gear, or from constructions wherein the weight of the heavier materials must overcome a counterweight before there is actuation of the outlet ports.

From the foregoing it will be apparent that I have devised a simple, practical, and automatic means for regulation of separators which fully meets the requirements and fulfills the objects hereinbefore stated.

While the invention has been described and illustrated in connection with the em-

bodiments herein shown, it will be understood that I do not desire to limit myself to the precise construction of this disclosure, as many changes in the construction and arrangement of parts may be made without departing from the principles of the invention or sacrificing its chief advantages.

What I claim is:—

1. In a separator, a separating device having an outlet and outlet controlling means; a regulator comprising a float member; and mechanical instrumentality including a lost motion element, directly connecting said float and said controlling means. 75

2. In a separator, a separating device having an outlet port and means for opening and closing said port; a regulator comprising a float member; and a direct mechanical lost motion connection between said float member and said port opening and closing means. 80

3. In a separator, a separating device having an outlet and means for controlling said outlet; a regulator comprising a float member; and a lost motion lever mechanism connecting said float member and said controlling means. 90

4. In a separator, a separating device having an outlet and outlet controlling means; a regulator comprising a float member; and lever mechanism including a lost motion element, directly connecting said float member and said outlet controlling means. 95

5. In a separator, a separating device having an outlet and outlet controlling means; a regulator comprising a float member; and a direct mechanical connection between said float and said means, adapted to permit a limited movement of the float without effecting actuation of the outlet controlling means. 100

6. In a separator, a separating device having an outlet and outlet controlling means; a regulator comprising a float member; and a direct mechanical connection between said float and said means adapted to permit a limited movement of the float, during a portion of its stroke, without effecting actuation of the outlet controlling means and for the remainder of its stroke to directly and positively actuate said outlet controlling means. 105

7. In a separator, a separating device having an outlet and outlet-controlling means; a regulator comprising a float member mounted for reversible movement; and a direct mechanical connection between said float and said outlet-controlling means, the float having a connection adapted to permit a limited movement of the float when its movement is 110 reversed, without effecting actuation of the outlet-controlling means, and for the remainder of its movement to positively and directly actuate said outlet-controlling means. 115

8. In a separator, a separating device having an outlet and outlet-controlling means; a regulator comprising a float member mounted for reversible movement; and a direct mechanical connection between said float and said outlet-controlling means, the float having a connection adapted to permit a limited movement of the float when its movement is 120 reversed, without effecting actuation of the outlet-controlling means, and for the remainder of its movement to positively and directly actuate said outlet-controlling means. 125

8. In a separator, a separating device adapted to cause lateral movement of materials to be separated, and having an outlet and outlet-controlling means; a regulator member; means comprising mechanical instrumentalities having a lost motion connection connecting said regulator member and said outlet-controlling means; and means for restraining and guiding the movements of the regulator member.
- 5 9. In a separator, a separating device having a material supporting bottom, an outlet, and means for controlling said outlet; a regulator comprising a float member; means including a mechanical lost motion element, directly connecting said float member and said outlet controlling means; and means including a member associated with the float and passing through an opening in said bottom, for guiding the movements of the float member.
- 10 10. In a separator, a separating device having an outlet and outlet controlling means; a regulator comprising a float member; a direct mechanical lost motion connection between said float member and said outlet controlling means; and means for effecting an adjustment of the float member and the outlet controlling means with relation to a stratum of the material to be separated.
- 15 11. In a separator, a separating device having an outlet and outlet controlling means; a regulator comprising a float member; a direct mechanical lost motion connection between said float member and said outlet controlling means; and means comprising adjusting members and a counter-weight, for effecting an adjustment of the float member and the outlet controlling means with relation to a stratum of the material to be separated.
- 20 12. In combination, a separator having an outlet and outlet controlling means; a float member having parallel sides proportioned in height to extend to the surface level of materials to be separated; and connected with the outlet controlling means at a point above the surface level of materials in the separator.
- 25 13. In combination, a separator having an outlet and outlet controlling means; a float member having a body portion extending above the surface level of materials to be separated, and including vertical sides; only the vertical sides being adapted to be immersed in the materials to be separated; said float connected to the outlet controlling means, at a point above the surface level of materials in the separator.
- 30 14. In combination, a separator having an outlet and outlet controlling means; a float member including a body portion adapted to rest at its lower portion upon a stratum of the heavier materials to be separated, and
- 35 proportioned in height to extend up through and above the surface level of the materials; a top portion having sloping sides, disposed on said body portion above the surface of the materials; and means for connecting said float with said outlet controlling means.
- 40 15. In combination, a separator having an outlet, a material supporting bottom, and outlet controlling means; a float member including a body portion having vertical sides, said body portion being adapted to rest, at its lower portion upon the surface of a stratum of the heavier materials on the bottom of the separator, and proportioned in height to extend up through and above the level of the materials in the separator; a top portion having sloping sides, disposed upon said body portion; and means, including a lost motion element, disposed upon said body portion and connecting said float member with said outlet controlling means.
- 45 16. In combination, a separator having an outlet, a material supporting bottom, and outlet controlling means; a float member including a body portion having vertical sides, said body portion being adapted to rest, at its lower portion upon the surface of a stratum of the heavier materials on the bottom of the separator, and proportioned in height to extend up through and above the level of the materials in the separator; a top portion having sloping sides, disposed upon said body portion; means, including a lost motion element, disposed upon said top portion and connecting said float member with said outlet controlling means; and a guide member secured to the body portion and passing through an opening in the bottom of the material support.
- 50 17. A separator having a receptacle for materials to be separated, having outlets for heavier and lighter portions thereof respectively, means for controlling the opening and closing of said outlets and means for affecting stratification of the materials in the separator; a regulator comprising a float member weighted to normally rest upon the surface of a stratum of the heavier materials and extend up through and above the level of the materials in the receptacle; a supporting instrumentality movably mounted in operative relation to said receptacle; link mechanism connecting said supporting instrumentality and said outlet controlling means; adjusting means associated with said link mechanism; lever mechanism associated with said supporting instrumentality and operatively connected with said link mechanism; mechanical lost motion mechanism connecting said float member and said lever mechanism; an adjusting means associated with said connections; and a counter weight associated with said lever and link mechanisms.
- 55 18. In a separator, a separating device

- having an outlet and movable outlet-controlling means; a regulator member for actuating the outlet controlling means; and mechanical means connecting said regulator member and said outlet-controlling means, the connection being adapted to permit an up and down movement of the regulator member in addition to its outlet control actuation. 5
19. A separator having a material-supporting device including an outlet and outlet-controlling means; a supporting instrumentality associated therewith; an arm mounted on and movable with said supporting instrumentality; a lever connected to said supporting instrumentality; a regulator member connected to said lever, and adapted to actuate the outlet control means, the connection being adapted to permit an up and down movement of the regulator member in addition to its outlet controlled actuation; and mechanical means connecting said lever and said outlet-controlling means. 10
20. A separator having a material-supporting device including an outlet and outlet-controlling means; a supporting instrumentality associated therewith; an arm mounted on and movable with said supporting instrumentality; a regulator member connected to said lever, and adapted to actuate the outlet control means, the connection being adapted to permit an up and down movement of the regulator member in addition to its outlet controlled actuation; and mechanical means connecting said lever and said outlet-controlling means. 15
21. A separator having a material-supporting device including an outlet and outlet-controlling means; a supporting instrumentality associated therewith; an arm mounted on and movable with said supporting instrumentality; a lever connected to said supporting instrumentality; a regulator member connected to said lever, and adapted to actuate the outlet control means, the connection being adapted to permit an up and down movement of the regulator member in addition to its outlet controlled actuation; mechanical means connecting said lever and said outlet-controlling means; and means for effecting an adjustment between said regulator and said lever. 20
22. The combination in a separator having a material-supporting device, outlets for heavier and lighter portions of the material, and a gate over which the lighter and under which the heavier materials pass to said outlets; of a regulator member for actuating said gate; and mechanical instrumentalities having a lost motion connection connecting said regulator member and said gate, the connection being adapted to permit an up and down movement of the regulator member in addition to its outlet control actuation. 25
23. In a separator, a separating device adapted to cause a lateral movement of materials to be separated, and having outlets for heavier and lighter portions of the material; a gate over which the lighter and under which the heavier portions of materials pass to said outlets; a regulator member; means, comprising mechanical instrumentalities having a lost motion connection connecting said regulator member and said gate; and means for restraining and guiding the movements of the regulator member. 30
24. In combination, a separator having an outlet; means for controlling the opening and closing of said outlet; a supporting instrumentality; mechanical means connecting said supporting instrumentality and said outlet controlling means; a float member; and instrumentality including a mechanical lost motion connection, associated with said supporting instrumentality and connecting said float member and said outlet connecting means. 35
25. The combination in a separator having an outlet and outlet controlling means, of a supporting instrumentality mounted movably in operative relation to the separator; an arm disposed on and movable with said supporting instrumentality; mechanism connecting said arm and said outlet controlling means; means for effecting an adjustment between said mechanism and said arm; lever mechanism mounted on said supporting instrumentality and operatively connected with said arm; a float member; a mechanical lost motion connection between said float and said lever; means for effecting an adjustment between said float and said lever; means for guiding the movements of the float member; and means, comprising a counterweight disposed on said supporting instrumentality, for adjusting the weight of the float member. 40
26. The combination in a separator having a material supporting device, outlets for heavier and lighter portions of the material, and a gate over which the lighter and under which the heavier materials pass to said outlets, of a regulator comprising a float member; a mechanical lost motion connection between said float member and said gate; and means for effecting an adjustment between the bottom of the float member and bottom of the gate. 45
27. The combination in a separator having a material supporting device, outlets for heavier and lighter portions of the material, and a gate over which the lighter and under which the heavier materials pass to said outlets, of a regulator comprising a float member; a mechanical lost motion connection between said float member and said gate; and means for effecting an adjustment between the bottom of the float member and bottom of the gate. 50

which the heavier materials pass to said outlets; of a regulator comprising a float member; mechanism including a lost motion instrumentality, connecting said float member and said gate; and means for effecting a balance between the float and the gate.

28. A separator having a receptacle for materials to be separated, having outlets for heavier and lighter portions thereof respectively, means for controlling the opening and closing of said outlets and means for effecting stratification of the materials in the separator; a regulator comprising a float member weighted to normally rest upon the surface of a stratum of the heavier materials in the receptacle and extend up through the lighter materials and above the level of the materials in the receptacle; a supporting instrumentality movably mounted in operative relation to said receptacle; mechanism operatively connecting said supporting instrumentality and said outlet controlling means; a lever mechanism operatively connected with said supporting instrumentality; and a mechanical lost motion instrumentality connecting said lever and said float member.

29. A separator having a receptacle for materials to be separated, having outlets for heavier and lighter portions thereof respectively, means for controlling the opening and closing of said outlets and means for effecting stratification of the materials in the separator, said means being adapted to cause a lateral movement of the materials; a regulator comprising a float member weighted to normally rest upon the surface of a stratum of the heavier materials and extend up through and above the level of materials in the receptacle; a supporting

instrumentality movably mounted in operative relation to said receptacle; link mechanism connecting said supporting instrumentality and said outlet controlling means; adjusting means associated with said link mechanism; lever mechanism associated with said supporting instrumentality and operatively connected with said link mechanism; mechanical lost motion mechanism connecting said float member and said lever mechanism; adjusting means associated with said connection; a counterweight associated with said lever and link mechanisms; and means for restraining and guiding the movements of the float member.

30. The combination in a separator comprising a liquid tank, a screen for the reception of materials to be separated, means for pulsating liquid therethrough, there being outlets for the heavier and lighter portions of the material and a gate having a lower surface under which the heavier and an upper surface over which the lighter materials pass to said outlets, of a regulator therefor comprising a float member adapted to normally rest on the surface of the heavier materials; and means, including a mechanical lost motion mechanism, connecting said float and said gate, whereby the lower portion of the gate and the bottom of the float member are maintained in predetermined positions with relation to the surface of the heavier materials on the screen.

In testimony whereof I affix my signature in the presence of two subscribing witnesses.

MICHAEL HENRY REAP.
